UNITED STATES PATENT OFFICE.

ROBERT M. McLAIN AND WILLIAM M. QUICK, OF HUNTSVILLE, ALABAMA, ASSIGNEES,
BY DIRECT AND MESNE ASSIGNMENTS, TO THE QUICK-MCLAIN MACHINE GUN
COMPANY, A CORPORATION OF ALABAMA.

MACHINE-GUN.

1,375,653.

Specification of Letters Patent. Patented Apr. 19, 1921.

Application filed June 1, 1917. Serial No. 172,253.

To all whom it may concern:

Be it known that we, ROBERT M. McLAIN and WILLIAM M. QUICK, citizens of the United States, residing at Huntsville, in the county of Madison and State of Alabama, have invented certain new and useful Improvements in Machine-Guns; and we do hereby declare the following to be a full, clear, and exact description of the invention, such as will enable others skilled in the art to which it appertains to make and use the same.

This invention is a gun of the rapid fire type designed more particularly for use by mobile troops, although the invention is equally adapted for employment in connection with guns of larger caliber, such as are used in fortifications.

In practice, rapid fire guns and field guns are supplied with fixed ammunition; that is to say, the projectile or shell is mounted in its cartridge shell containing the explosive or gas forming mixture, such as powder, and a percussion cap carried by the cartridge shell. This type of ammunition is designed to facilitate the work of the attendants in the loading and firing of the gun. Ammunition of this class is expensive to manufacture, not only as to materials, but in the time and labor involved. Such ammunition is also bulky, of great weight, and has the further disadvantage of being dangerous to handle and transport. Moreover, in rapid fire guns using rifle cartridges, it is necessary that the cartridges be properly fed into the machine to be discharged, and this feeding operation requires the services of attendants in loading the belts or cartridges, or in attending a part of the device for feeding the gun.

A purpose of this invention is to overcome the many objections relative to guns having ammunition of the fixed or separated types and to thereby provide an effective arm which will be safe to operate, and which will not require the services of so many attendants during the feeding and firing of the gun.

A further object of the invention is to provide a gun wherein the projectiles may be automatically fed to the barrel for discharge therefrom by an explosion in the breech of

the gun due to the ignition of a combustible substance formed of an explosive aeriform fluid, thereby eliminating the weight of the loaded cartridge shell for rapid fire guns or field guns, or the weight and the handling of the explosive charge of the larger caliber guns.

A further aim of the invention is to provide a simple and efficient gas gun which can be automatically fired in different directions, the gun being positive in action and powerful, as well as employing an explosive which is comparatively smokeless.

Other objects and advantages of the invention will become apparent from the following detailed description thereof taken in connection with the accompanying drawings, wherein one embodiment of the invention is disclosed. It is to be understood however, that the construction set forth in the drawings is for the purposes of illustration only, and not as defining the limits of the invention, the scope of the invention being determined by the appended claims.

In the drawings:—

Figure 1 is a longitudinal sectional view through the gun disclosing an internal combustion engine, a barrel, and a projectile feeding mechanism.

Fig. 2 is an enlarged detail sectional view through the feeding mechanism of the gun.

Fig. 3 is an enlarged plan view disclosing the feeding mechanism.

Fig. 4 is an enlarged detail view of the loading sleeve.

Fig. 5 is an enlarged detail view of the means for effecting pivotal movement of the gun upon its support.

The gun comprises a barrel, associated with which is an internal combustion engine, or any equivalent therefor, and projectile feeding instrumentalities automatically operated by the movement of the engine to feed projectiles successively to the barrel after each explosion of the combustible mixture, and preferably at the commencement of the intake stroke of the engine, the explosion of the engine discharging the projectile which is positioned at the breech end of the barrel. The gun is mounted in any suitable manner for universal firing, and mechanism is employed whereby

the operation of the engine may be utilized to effect an automatic oscillatory movement of the gun so that the barrel may discharge its projectiles successively in various directions.

The gun may be mounted upon any suitable support, such as a tripod indicated at 1, and having a base plate 2, which may be stationary on the tripod. Coöperating with the stationary base plate 2 is shown a wear plate 3, which is preferably pivotally mounted by means of the bolt 4 on the tripod or supporting element. This wear plate serves to support any suitable mechanism for changing the angle of firing of the gun, such for example, as a sector gear 5 pivotally mounted at 6 upon supports 7, the gear being moved to various positions by means of a worm 8 rotatable by manually controlled means 9. Mounted above the sector gear 5 is the breech end of the gun, which is formed in a casting 10. This casting may have air cooling vanes 11, or any equivalent means for cooling the engine. The explosive chamber of the engine is indicated at 12, and shown formed within the casting 10. Within this chamber there is shown a piston 13 having a piston rod 14 which is connected to a wheel 15 mounted within a circular portion 16 of the casing. This portion of the casing may be provided with a handle 17 for manually controlling the fire of projectiles through the gun barrel 18. The engine may be of any approved type or form, and may be provided with a magneto 19 and the usual timing mechanism and carburetor, not shown. The casting 10 may have a plate 20 secured thereto by any suitable means, and this plate may serve to mount a hopper 21, or any other suitable feeding device. The plate 20 is provided with an aperture 22, which registers with a passage 23 formed in the casting 10, said passage being controlled by a projectile feeding element shown in the form of a rotatable sleeve 24, having a passage 23^a registering with the passage 23. This sleeve is shown provided with a collar 25 near its upper end, which is engaged by the plate 20 to preclude the upward movement of the sleeve out of the casting 10. The sleeve is preferably provided with an opening registering with the passage 23 of the casting, said opening leading in from the side of the sleeve to discharge projectiles through the bottom of the sleeve indicated at 26. Near the lower end 26 of the sleeve, there may be provided a movable trip 27 to engage projectiles moving toward the barrel. The upper end of the sleeve 24 is preferably provided with resilient means indicated at 28 to maintain the sleeve in a predetermined position, so that its passage will not register with the passage 23 through the casting 10, thereby shutting off

any escape of gases from the chamber 12 through the end 26 of the sleeve, and thence out through the passage 23 of the casting.

The loading operation of the gun is preferably controlled automatically by the movement of the engine, although it is obvious it can be manually controlled. The loading sleeve being maintained in a predetermined closed position by its resilient means 28, may be moved to its opened position by suitable means, such as the control rod 29, which is shown connected with an arm 30 extending from the sleeve 24, said rod 29 being shown guided in its movement by a guide block 31. The rod is capable of reciprocating movements, and may be reciprocated by a cam 32 carried by the magneto 19, or by any other part of the engine mechanism, whereby the loading sleeve 24 may be moved to its opened position against the action of the spring 28 at a predetermined interval of the movement of the engine. It is preferred that this loading operation through the sleeve to the barrel of the gun be effected at the commencement of the intake stroke of the engine, whereby such action of the engine will serve to draw a projectile indicated at 33 past its trip 27 into that portion of the gun between the barrel 18 and the explosion chamber 12 of the engine. Such portion may be indicated as the breech of the gun, and is shown at 34. It is preferred to provide the breech end 34 of the gun with suitable means to preclude the movement of the projectiles 33 from the firing position desired within the gun. To accomplish this purpose, there may be provided suitable retaining means, such as the expansible rings 35, 36, the ring 35 being interposed between the chamber 12, and the space 37 to be occupied by the projectile 33, and thereby limit the movement of the projectile 33 toward the chamber 12 during the suction stroke of the engine. The ring 35 may be of such diameter as to preclude the passage of a projectile through the same. The ring 36, however, is preferably of a diameter which will permit of the passage of the projectile 33 through the ring when sufficient force is generated by an explosion in the chamber 12 to drive the same through the ring 36, and through the barrel 18 of the gun. It is obvious that any equivalent means may be employed to the retaining means 36 to facilitate the passage of the projectile from the chamber or space 37 between the chamber 12 and the barrel 18. By this arrangement, the feeding of the projectiles to the firing position within the gun is automatically controlled by the action of the engine, and the explosion of the combustible mixture in the chamber 12 serves to force the projectile in the space 37 from the gun and through the barrel 18, after which the further movement of the engine

on the commencement of its intake stroke will suck in another projectile through the sleeve 24 to the space 37 in the breech 34 of the gun.

5. If desired, the gun may be provided with a cut-off valve 47 positioned in rear of the space 37. The valve 47 is shown comprising a cylindrical body portion 48 rotatably mounted in the casting 10 transversely of the discharge passage from the engine. The valve is shown having a solid face 49 and a perforated face 50 whereby communication between the chamber 12 of the engine and the chamber 37 of the breech may be made 15 or broken as desired. To rotate the valve into its desired position, a handle 51 may be provided so that the engine may be operated without discharging projectiles from the barrel, and thereby cutting off the discharge of gases through the barrel of the gun. When this condition exists, the exhaust gas from the engine is discharged through a suitable exhaust valve 52 instead of through the barrel 18 of the gun.
- 20 25 The chamber 12 may be provided with the usual intake port 38 and with a spark plug 39, or any equivalent structure.

A further feature of the invention resides in the automatically operating means to effect an oscillatory movement of the gun on its support 1. This may be effected by any suitable means, one form of which is shown as a telescopic shaft 40 having a pinion 41, which engages a gear 42 of the engine mechanism to transmit motion to the shaft 40. One end of the shaft may extend through the plate 3 of the support, if desired, and terminate in a crank arm 43. This crank arm may be connected to the stationary base plate 2 by means of a link 44, which is pivoted at 45 to the base plate 2, and pivoted at 46 to the crank arm 43. By this arrangement, the rotation of the shaft 40 by the movement of the engine, will serve to 40 45 effect an oscillatory movement of the gun and thereby permit the gun to fire projectiles automatically in various directions.

Having thus described our invention, what we claim as new is:—

- 50 55 60 65 70 75 80 85 90 95 100 105 110 115 120 125 130 1. A gun comprising a barrel, an internal combustion engine having its explosive chamber opening into one end of the barrel, and projectile feeding instrumentalities operable automatically by the movement of the engine to supply projectiles successively to the barrel to be discharged through the barrel by explosions in the combustion chamber of the engine.
2. A gun comprising a barrel, an internal combustion engine having its explosive chamber opening into one end of the barrel, projectile feeding instrumentalities operable automatically by the movement of the engine to supply projectiles to the barrel 65 to be discharged therefrom by explosions

in the engine chamber, a support for pivotally mounting the gun, and means operated by the engine to automatically move the gun on its pivot.

3. A gun comprising a barrel, an internal combustion engine having its explosive chamber opening into one end of the barrel whereby the force of the explosion may be expended through the barrel, means to supply projectiles to the barrel to be discharged therefrom by explosions in the engine chamber, a support for pivotally mounting the gun to permit of substantially universal movements of the gun on said support, and means operated by the engine to automatically effect an oscillatory movement of the gun.

4. A gun comprising a barrel, an internal combustion engine in coöperative relation to the barrel, a support for pivotally mounting the gun provided with a base plate, and a shaft rotatable by the engine and having means of connection with the base plate for effecting pivotal movement of the gun on its support.

5. A gun comprising a barrel, an internal combustion engine coöperating therewith, a support for pivotally mounting the gun, said support having a stationary base plate and a movable wear plate coöperating with the base plate, a shaft having means to effect its rotation by the movement of the engine, said shaft having a bearing in said wear plate and provided with a crank arm adjacent the base plate, and means to detachably connect the crank arm with the base plate to effect an oscillatory movement of the gun during the running of the engine.

6. A gun comprising a barrel, an internal combustion engine coöperating therewith and having its explosive chamber opening into one end of the barrel, projectile retaining means positioned near one end of the barrel, a projectile feeding element to successively supply projectiles to the retaining means of the barrel, and means controlled by the operation of the engine to shut off the projectile feeding means during the explosion of a combustible mixture within the engine.

7. A gun comprising a barrel, an internal combustion engine coöperating therewith, a loading sleeve carried by the gun to supply projectiles to the barrel adjacent its juncture with the explosive chamber of the engine, means to maintain said sleeve in a predetermined position to cut off the supply of projectiles to the barrel, and a rod actuated by the movement of the engine to effect the movement of the loading sleeve against the action of its retaining means to supply projectiles to the barrel at predetermined intervals during the operation of the engine.

8. A gun comprising a barrel, an internal

combustion engine coöperating therewith, whereby the force of the explosion from the engine may be expended through the barrel, a movable loading sleeve to supply 5 projectiles successively to the barrel, resilient means to retain the sleeve in a position to preclude the passage of combustible mixture through the sleeve and to thereby compel the exploding gases to pass through 10 said barrel, and means connecting a part of the engine mechanism with said sleeve to actuate said sleeve to its projectile feeding position when the piston of the engine is at a predetermined position relative to said 15 barrel for the purpose of drawing a projectile from said sleeve to its firing position in the barrel.

9. A gun comprising a barrel, an internal combustion engine having its explosive 20 chamber opening into one end of the barrel, projectile retaining means in the form of expansible rings positioned in the breech of the barrel to engage and limit the movement of projectiles fed to the barrel, a ro- 25 tatable loading sleeve for automatically supplying projectiles to the barrel, resilient means to retain said sleeve in a predetermined position to preclude the escape of gases through said sleeve from the explosive 30 chamber, a cam rotatable by said engine, and a trip rod interposed between the

cam and said sleeve to move the sleeve to its loading position when the piston of the engine is at a predetermined position.

10. A gun comprising a barrel, an internal combustion engine in coöoperative relation thereto for expending the force of explosion of the engine through said barrel, a sleeve to supply projectiles to the barrel to be discharged therethrough by explosions 40 within the engine, resilient means to maintain said sleeve in a position to preclude the passage of explosive gases therethrough, and means actuated by the movement of the engine to move said sleeve to a position to 45 supply projectiles successively to the barrel at the commencement of the intake stroke of the engine.

11. A gun comprising a barrel, an internal combustion engine in coöoperative relation thereto and adapted to expend the force of the explosion of the engine through said barrel, means to supply projectiles to the barrel, and means to cut off the communication between the engine and barrel, 50 said means permitting of the force of the explosion to be discharged otherwise than through the barrel of the gun.

In testimony whereof we affix our signatures.

ROBERT M. McLAIN.
WILLIAM M. QUICK.
